UNITED STATES PATENT OFFICE.

HENRY O. WOY, OF GREEN CITY, MISSOURI.

WEATHER-STRIP.

SPECIFICATION forming part of Letters Patent No. 400,813, dated April 2, 1889.

Application filed March 1, 1888. Serial No. 265,788. (No model.)

To all whom it may concern:

Be it known that I, HENRY O. WOY, a citizen of the United States, residing at Green City, in the county of Sullivan and State of Missouri, have invented certain new and useful Improvements in Weather-Strips; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to certain new and useful improvements in weather-strips; and it consists in the combination and arrangement of parts hereinafter described and claimed.

The objects of my invention are to prevent 20 the ingress of cold wind, rain, or snow between the sill and lower edge of the door, and, furthermore, to drain the sill from any surplus of moisture that at any time may accumulate thereon.

25 Reference being had to the drawings accompanying this application and forming part of the same, Figure 1 is a front elevation of my invention, showing parts in place with the door closed. Fig. 2 is a vertical cross-section 30 of sill and weather-strip, and Fig. 3 is a longitudinal sectional view.

Similar letters refer to like parts throughout the drawings.

Referring to the drawings, A represents a 35 door-frame, provided with an inwardly-projecting sill, B, having at one end an upwardly-curved hollow projection, a, the inner edge of which extends flush with the inner edge of door-frame A. The opposite end of 40 sill B is formed with an upright solid projection, a', over which and extending down its inner face is secured a metal bearing-strip, b, having a perforation, b'.

Between extensions a and a' the sill B is 45 formed with a longitudinal recess, c, extending to the inner wall of projection a, and directly in front of same a deeper parallel recess, c', is formed in sill B, extending to the same point in projection a. A metal end-bearing strip, d, having a perforation, d', is 50 secured to the inner wall of projection a, and

forms a bearing for one end of the metal weather-strip C, which has a flat upper surface, e, and at one end a curved upward projection, e', the outer edge of which is formed 55 vertical in line with the edge of strip C. Curved projection e', secured to strip C near the inner edge of projection a, moves in line with said edge and the inner edge of the frame A, and operates the weather-strip C 60 when the door D is opened or shut. The under face of strip C is provided with extension f, which normally (that is, when the door is open) is flush with the frame, and only becomes visible when the door is closed, having end 65 bearings f' and f'', said end bearings being arranged to loosely fit in perforations b' and d', as shown in Fig. 3, whereby the strip C is loosely held in place with its upper edge flush with the upper face of the door-sill. Tubes 70 g extend from the inner face of recess c' downward through the sill and floor for the purpose of drainage, carrying off the water in said recess. Door D is hung by hinges h to one side of frame A, and to the opposite 75 side is secured a retaining-lock, h'. Below the lock h' a spring-bar, I, is secured to the inner face of door D, near its edge, extending downward to the lower edge of the door, and terminating in a right-angular projection, j, which, when the door is being shut, strikes against the vertical edge of curved projection e', forcing it toward the frame A, raising the edge of the strip C toward the door D, and as the movement of the door is continued the end of the bar I passes over the edge of strip C, pressing it to the lower face of the door. When the door D is tightly shut, the upper face of strip C is held vertically 80 against the lower inside face of door D, thus 85 preventing any ingress of wind, rain, or snow, and making a tight joint. Opening the door D forces the strip C back to its place by contact with the lower edge of said door. The inwardly-projecting sill B serves as a carpet- 90 strip, protecting the same from the weather, as the moisture is carried off through the recesses and drain-pipes.

Having described my invention, what I claim, and desire to secure by Letters Patent, 100 is—

The frame A, having the grooved sill B, in

combination with the weather-strip C, provided with a projection, e' , and an extension, f , whose terminal axes $f' f^2$ are pivotally secured in slots in the sides of the frame, which 5 normally lies flush with the frame, and the door D, having the plate I, provided with a projecting lug, j , whereby the arc-like oscillation of said lug operates the weather-strip in either direction, respectively, to engage and

disengage the strip by reason of the projection e' , for the purpose set forth.

In testimony whereof I affix my signature in presence of two witnesses.

HENRY O. WOY.
